(57) **CLAIM**

I claim the ornamental design for a folding exercise bench, as shown.

DESCRIPTION

FIG. 1 is a front perspective view of a folding exercise bench in a first exercise position, showing my new design;
FIG. 2 is a front elevational view thereof;
FIG. 3 is a right side elevational view thereof;
FIG. 4 is a left side elevational view thereof;
FIG. 5 is a top plan view thereof;
FIG. 6 is a rear elevational view thereof;
FIG. 7 is a bottom plan view thereof;
FIG. 8 is a front perspective view of the folding exercise bench of FIG. 1, showing the bench in a second exercise position;
FIG. 9 is a right side elevational view of the bench in the position of FIG. 8;
FIG. 10 is a rear perspective view of the bench in the position of FIG. 8;
FIG. 11 is a front perspective view of the folding exercise bench in a lowered, folded position;
FIG. 12 is a right side elevational view of the bench in the position of FIG. 11; and,
FIG. 13 is a rear perspective view of the bench in the position of FIG. 11.
